METHOD OF MAKING CAST BOXES

Marshall G. Zavertnik, Manchester, Mo., and Clarence H. Rongey, Granite City, Ill., assignors to Killark Electric Manufacturing Company, St. Louis, Mo., a corporation of Missouri

Filed Aug. 26, 1963, Ser. No. 304,452

7 Claims. (Cl. 22—133)

The present invention relates to a method of making cast boxes and molds for such boxes. Such boxes are capable of use in a number of connections but are particularly useful in areas where there is an explosive or combustible atmosphere, as junction boxes that can be made dust tight and explosion-proof, so that they can enclose electrical equipment that is subject to sparking.

Such boxes are required in many cases to have in-turned or out-turned flanges on the top, sometimes with upstanding rims on the flanges. Heretofore it has been customary to fabricate these boxes from sheet metal, then weld, grind, drill, tap and finish them. Such fabricated boxes are costly, less strong and rigid, and more likely to fail to be explosion-proof than is the box made by the present method. Yet prior casting of such boxes has been excessively expensive, since it has required the use of baked cores or the like. It is a principal object of the present invention to provide a method of manufacturing a mold for casting such boxes, and particularly to provide such a method that does not involve the use of baked cores.

It is a further object of the invention to provide a method of this kind that has a minimum number of mold parts for a maximum variety of boxes, which may differ in depth and in top flange construction.

Basically, the present invention involves the parting of the mold at the top of the sidewall of the box. The flange mold is formed in a drag and the box mold is formed in a cope. The box mold includes a green sand core resting on top of the drag mold.

This arrangement enables the flanging pattern to be formed as part of or attached to one side of a pattern plate. Therefore different flange patterns can be used with any correspondingly sized box pattern. The arrangement also enables the same pattern plate to have one kind of flange pattern on one face and a different kind of a flanging pattern on its opposite face. In such ways, the present system reduced the amount of equipment required for a complete line of boxes.

Another feature of the present invention lies in the fact that with the box section having straight vertical sides, boxes of different depths can be made from the same box pattern by the expedient of having inserts and ring plates that constitute supplemental parts for the pattern to make it different in effective depth.

Other objects and features of the invention will appear from the description of the process to follow.

In the drawings:

FIGURE 1 is a perspective view of a box made in accordance with the present method;

FIGURE 2 is a characteristic longitudinal section through the box of FIGURE 1;

FIGURE 3 is a fragmentary section similar to the left side of FIGURE 2 but with a different type of top flanging, this flange being turned outwardly;

FIGURE 4 is a view similar to FIGURE 3, but with the flanging extending outwardly and then upwardly;

FIGURE 5 is a view similar to FIGURE 3 but with the flanging turned inwardly;

FIGURE 6 is a view partly in section showing a match plate with a flange pattern on each of its opposite sides;

FIGURE 7 is a view of a drag mold made in accordance with one of the flanged patterns of FIGURE 6;

2

FIGURE 8 is a fragmentary view of another pattern plate similar to that of FIGURE 6 but with different flange patterns;

FIGURE 9 is a view of a step in the manufacture of a green sand core for the box;

FIG. 10 is a view of a stage in the process of making the mold wherein the green sand core has been applied to the flange mold shown in FIGURE 7;

FIGURE 11 is a view showing the manufacture of the 10 principal box mold in the cope;

FIGURE 12 is a view showing the stage at which the box mold in the cope, after the pattern has been drawn, has been applied and matched to the flange mold in the drag;

15 FIGURE 13 is a view of the manufacture of a box mold on a pattern where it is desired to reduce the depth of the box; and

20 FIGURE 14 is a view of the manufacture of the green sand core for the box using the deep pattern but producing a shallower box.

As illustrated in FIGURE 1, the box 20, is, generally speaking, rectangular in cross-section. It can have other shapes, but should not have undercut side walls below the flanges. FIGURE 2 shows this same box in longitudinal cross-section, as having an in-turned flange 21 around the top, the inner rim of which extends upwardly as shown at 22. Feet 23 may be applied separately to the box.

In order to cast a box with an in-turned flange, such 30 as is illustrated in FIGURE 2, it has heretofore been conventional to use a baked core which is destroyed after the casting is made. The present invention makes the box with a wholly green sand mold.

The first stage in the manufacture of the mold includes 35 the making of a flange mold in a drag, such as the one as illustrated in FIGURE 7. To make this mold, a match plate 30, or the like, can have a flange pattern 31 mounted on one of its faces. A different flange pattern 32 is mounted on the opposite plate.

With the plate 30 resting on some support and forming a bottom, the drag 33 is mounted over the plate 30 and suitably located by familiar matching means. Sand 34 is then rammed into the drag 33 around the 45 pattern 31. The foregoing would be similar to, but inverted from the position illustrated in FIGURE 7.

After the sand is suitably rammed, the pattern, sand and drag assembly is reverted to the position of FIGURE 7, and the pattern is drawn as is suggested by the 50 dashed lines between FIGURE 6 and FIGURE 7, leaving a flanged mold cavity as it appears in FIGURE 7. This cavity is usually a complete, closed rectangle, leaving an "island" surrounded by the channel-like cavity.

If the match plate 30 is inverted, so that the pattern 55 32 formed the cavity, the flanging illustrated in FIGURE 4 will result. If the match plate 37 illustrated in FIGURE 8 is used, with the pattern 38, the flanging of FIGURE 5 will be formed. If the plate 37 is used with the pattern 39, the flanging of FIGURE 3 will be formed.

In any case, after the drag mold has been formed as 60 illustrated, then a green sand core is formed from the box pattern. This is illustrated in FIGURE 9. A hollow box pattern 42, which has the shape of the ultimate box below the flange, is filled with sand 43 and rammed. A plate 44 is then applied over it and the cope mold is reverted. It is lifted from the plate 44, and placed over the drag mold of FIGURE 7, resting upon the sand at the parting line, and on the "island" within the flange cavity. As illustrated, it overhangs the flange cavity. 65 Thereupon the pattern 42 is withdrawn, leaving the green sand core 43 in place over the drag mold, as appears in FIGURE 10. (We note that it is to be understood that 70

appropriate draft provisions are made to enable the various patterns to be drawn.)

The next step is to insert the box pattern 42 into a cope 46 on a plate 57 as is illustrated in FIGURE 11, closed end up. Sand 48 is then rammed around and over the pattern 42. This assembly is then inverted and the pattern 42 drawn, leaving the box mold cavity in the cope 46. The cope mold is then reverted and applied to the drag mold of FIGURE 7, as appears in FIGURE 12, employing the usual matching means.

As seen in FIGURE 12, there is a mold cavity that involves a continuous flange cavity 50 and box cavity 51. The risers and gates are not illustrated, since they can be formed where necessary.

It should be evident that the foregoing system provides a mold arrangement for making a flanged box that does not require the use of any baked cores or the like, but rather that can be made wholly from green sand. The box can have overhanging flanges. Also, a single box mold and pattern can be used with various flange patterns to provide the box with any selected flanging arrangement without requiring additional coring or additional patterns.

As shown in FIGURES 13 and 14, the same patterns can be used to make boxes of different heights. The box pattern 42 in FIGURE 13 is shown upon a plate 56. Around the pattern a supplemental "ring" plate 57 is fitted and raised above the plate 56 by spacers 58. The cope 46 rests upon the ring 57. In this case the box cavity in the sand 60 is of less depth than in FIGURE 11, although the pattern 42 is the same, and the length, breadth, and wall thicknesses, remain the same. For this arrangement, the green sand core must be shallower. This is shown in FIGURE 14 as being made from the same box pattern 42, but with a supplemental bottom plate 62 therein, spaced from the bottom of the pattern 42 by spacers 63. This gives a box green sand core 64 shallower than would otherwise be provided, and appropriate to the box mold 60.

By the supplemental ring 57 and the plate 62, the basic pattern can be used for many different depths of boxes, from quite shallow to quite deep. It is necessary to make the main pattern of the maximum depth and then to provide only the ring 57 and plate 62 with different spacers 58 and 63, to obtain a full line of boxes of this length and breadth, but of various depths. And any top flange pattern may be used for making any depth of box.

This method of molding not only makes a superior box, as set forth in an accompanying application, but also provides for many variations of a basic box, with a minimum of pattern parts.

Various changes and modifications may be made within the process of this invention as will be readily apparent to those skilled in the art. Such changes and modifications are within the scope and teaching of this invention as defined by the claims appended hereto.

What is claimed is:

1. In a method of molding a box that has a bottom, generally vertical side walls, and an overhanging flange on the side walls extending laterally therefrom, the steps of: making a flange mold by placing a drag onto a match plate having a rigid flange pattern thereon, which flange pattern has the shape of the box walls including the flange and above the same, and packing sand into the drag around the pattern and against the plate, removing the plate and drawing the pattern, thereby providing a mold having a flange cavity opening into its upper surface; forming in a box-like pattern a green sand core shaped like the interior side and bottom walls of the box below the flange, applying the same onto the flange mold to rest on the same inside the flange cavity, and drawing the pattern off the core; forming a side and bottom wall mold by packing sand around the sides and end, a rigid box-like pattern in a cope, which pattern is

shaped to form the outside of the side and bottom walls of the box and drawing the pattern to leave the cavity in the cope; inverting the said cope over the previously formed core and applying it to the flange mold, in proper alignment therewith; the side wall mold and the core within it forming a side wall cavity that registers with and opens into the flange cavity, the steps set forth forming a mold for a box having unitary bottom, side and flange walls.

10 2. In the method of claim 1, the steps of: forming the flange mold cavity of a shape that extends inwardly from the portions that form the box wall mold cavities, for the purpose of forming an inturned top flange on the box.

15 3. In the method of claim 1, the steps of: forming a flange mold cavity that is angular in cross-section, having a cavity portion that extends vertically, and a cavity portion that extends laterally from the vertical position, the vertically extending portion forming a wall part on the box above the flange.

20 4. In the method of claim 1, the steps of forming the green sand core in a hollow box pattern, that is then open at the top, then inverting the pattern containing the sand, applying the assembly over the flange mold and aligning it therewith, withdrawing the pattern, and thereafter completing the mold as aforesaid.

25 5. In the method of claim 1, the steps of: forming the box mold cavity by packing sand in a mold frame around sand above the outside of the same box pattern, then inverting the mold frame with the sand and pattern, withdrawing the pattern, and reverting the mold thus formed over the core and flange cavity, and matching them.

30 6. In the method of claim 1: the steps of inserting a plate in the box-like core pattern to form a false bottom thereto that is spaced from the normal bottom of the pattern, so that the core is shallower than the depth of the pattern, and in making the cavity for the side and bottom wall mold, the added steps of applying a ring around the outside of the box-like pattern adjacent the open end, and resting the cope on this ring, so that the cavity has a depth less than that of the pattern; these steps producing a mold for a shallow box from deep box patterns.

35 7. A mold for a box having bottom and side walls, and flanges extending laterally at the top of the side walls; the mold being formed in two mold frames, the frames parting the cavity below the laterally extending flanges; the lower frame having mold-forming material forming a flange cavity, and a convex green sand core portion for forming the interior walls of the box below

40 the flange, which green sand core portion is disposed upon and rises from the mold-forming material inside the flange cavity and above the parting; an upper frame resting upon the lower frame having mold-forming material forming a box cavity shaped to the size of the outside wall surfaces of the box below the flange; the upper frame disposing its cavity over the convex green sand portion and in registry with the flange cavity, the flange cavity consisting of a channel extending around the top of the mold-forming material, at the top of said material, with an island of the material within the channel, the convex core portion resting upon the said island, and overhanging the channel.

45 8. A mold for a box having bottom and side walls, and flanges extending laterally at the top of the side walls; the mold being formed in two mold frames, the frames parting the cavity below the laterally extending flanges; the lower frame having mold-forming material forming a flange cavity, and a convex green sand core portion for forming the interior walls of the box below

50 the flange, which green sand core portion is disposed upon and rises from the mold-forming material inside the flange cavity and above the parting; an upper frame resting upon the lower frame having mold-forming material forming a box cavity shaped to the size of the outside wall surfaces of the box below the flange; the upper frame disposing its cavity over the convex green sand portion and in registry with the flange cavity, the flange cavity consisting of a channel extending around the top of the mold-forming material, at the top of said material, with an island of the material within the channel, the convex core portion resting upon the said island, and overhanging the channel.

55 9. A mold for a box having bottom and side walls, and flanges extending laterally at the top of the side walls; the mold being formed in two mold frames, the frames parting the cavity below the laterally extending flanges; the lower frame having mold-forming material forming a flange cavity, and a convex green sand core portion for forming the interior walls of the box below

60 the flange, which green sand core portion is disposed upon and rises from the mold-forming material inside the flange cavity and above the parting; an upper frame resting upon the lower frame having mold-forming material forming a box cavity shaped to the size of the outside wall surfaces of the box below the flange; the upper frame disposing its cavity over the convex green sand portion and in registry with the flange cavity, the flange cavity consisting of a channel extending around the top of the mold-forming material, at the top of said material, with an island of the material within the channel, the convex core portion resting upon the said island, and overhanging the channel.
